UNITED STATES PATENT OFFICE

148,856

DESIGN FOR A XYLOPHONE

Eli H. Gruber, Malvern, Pa.

Application August 29, 1946, Serial No. 132,943

Term of patent 14 years

(Cl. D56—1)

To all whom it may concern:

Be it known that I, Eli H. Gruber, a citizen of the United States of America, residing at Malvern, in the county of Chester and State of Pennsylvania, have invented a new, original, and ornamental Design for a Xylophone, of which the following is a specification, reference being had to the accompanying drawing, forming part thereof.

Fig. 1 of the drawing represents a plan view of a xylophone showing my new design;

Fig. 2 represents a side elevation of the same; and

Fig. 3 represents an end elevation of the same.

I claim:

The ornamental design for a xylophone, as shown.

ELI H. GRUBER.
